SLICING AND SERVING KNIFE

Harry M. Gustafson, Chicago, Ill., assignor to Simmons Slicing Knife Company, Chicago, Ill.,
a corporation of Illinois

Application October 8, 1948, Serial No. 149,026

Term of patent 14 years

(Cl. D22—3)

To all whom it may concern:

Be it known that I, Harry M. Gustafson, a citizen of the United States, residing in Chicago, Cook County, State of Illinois, have invented a new, original, and ornamental Design for a Slicing and Serving Knife, of which the following is a specification, reference being had to the accompanying drawing, forming a part thereof.

Fig. 1 is a side view of a slicing and serving knife, showing my design;

Fig. 2 is a plan view of the slicing and serving knife; and

Fig. 3 is an end view of same taken from the right of Fig. 1.

I claim:

The ornamental design for a slicing and serving knife, as shown.

HARRY M. GUSTAFSON.
